UNITED STATES PATENT OFFICE.

JOSEPH H. POPE, OF HAMILTON, MASSACHUSETTS, ASSIGNOR TO UNITED SHOE MACHINERY COMPANY, OF PATERSON, NEW JERSEY, A CORPORATION OF NEW JERSEY.

MACHINE FOR TREATING STOCK.

1,123,369.

Specification of Letters Patent.

Patented Jan. 5, 1915.

Application filed January 27, 1908. Serial No. 412,841.

To all whom it may concern:

Be it known that I, JOSEPH H. POPE, a citizen of the United States, residing at Hamilton, in the county of Essex and Commonwealth of Massachusetts, have invented certain Improvements in Machines for Treating Stock, of which the following description, in connection with the accompanying drawing, is a specification, like reference characters on the drawing indicating like parts in the several figures.

This invention relates to improvements in machines for treating leather or similar material and in particular to machines intended to split died-out blanks to be used as counters, toe pieces, heel lifts or rands, or similar articles.

One object of this invention relates to the provision of a machine of the above class which is adapted to skive blanks in different patterns according to the various relations in which the completed articles are to be employed later, and which is adapted to be changed quickly from the manufacture of one form of article to that of another.

In the particular embodiment of this invention shown in the drawings, the form to be given the blank is determined by a mold or die removably mounted on a roll between which and a second pressure-applying roll the blanks are passed on their way to the stock treating means, which may be a fixed knife, and the change in the form to which the blank is skived is obtained by the use of one or the other of a plurality of differently shaped molds or dies, the particular mold or die to be used depending upon the shape it is desired to give to the blank.

Preferably a plurality of blanks such as referred to above are supported in a magazine from which they are fed forward singly to the rolls which present them to the knife. Preferably, also, the magazine will be adjustable to accommodate blanks of different sizes and the feeding means will be arranged to advance the blanks from the magazine toward the knife to a point at which the blank may be gripped by the mold or die-carrying roller and its co-operating pressure roller. Between these rollers the blank is molded into the proper form and is so held as it is fed forward into contact with the knife. It is usually desirable to pro-

vide means for adjusting the feeding means, above referred to, so that it may be adapted to feed blanks of different sizes to a position such that the forward edge of such blanks may be gripped by the rolls, and the provision of such means constitutes an important feature of the invention, while another feature consists in the provision of novel means for rendering the said feeding means inactive when desired.

The feeding means is arranged to feed the blanks so that they are gripped by the rolls at a certain position in the rotation of the rolls, this being desirable in order to enable the mold or die carried by one of the rolls to present the blanks to the knife in such manner that each part of the blanks will be skived to the form desired.

A further feature of the invention consists in the provision of means, separate from those above referred to, for determining the position in the rotation of the rolls at which the blanks shall be presented to them in proper position to be gripped and molded into the desired form before being presented to the knife. As the blank is engaged by the rolls or at any desired time thereafter, it will be engaged by the mold mounted on one of the rolls, which is preferably held rigidly against yielding away from the work. The other roll is preferably mounted in yielding bearings and yields to accommodate varying thicknesses of the work. It will be found, however, with the above which is an ordinary construction that many blanks, such as those for a horse shoe rand, tend to become displaced, as by spreading or yielding, as they are engaged preparatory to being fed to the knife, and another important feature of this invention consists in the provision of means such as guides mounted to engage the sides of the blanks as they are fed forward from the magazine to the rolls for preventing this displacement.

Other features of the invention consist in the construction of the lower roll and of a stripper therefor, and these as well as other details of construction in which reside still further features of the invention, will be more specifically referred to in the following description.

Referring to the accompanying drawings which illustrate my invention in the best

form known to me at this time, and in which,—

Figure 1 is a side elevation of a skiving machine; Fig. 2 is an end elevation; Fig. 3 is an isometric view showing the bed plate and connected agencies; Fig. 4 is an isometric view of a detail showing the knife, feed rolls and stripper; Fig. 5 is a vertical section on the line through the magazine, feed rolls and knife; Fig. 6 is an elevation showing the action of the mold on the stock; Fig. 7 is an isometric view of a detail showing work being fed to the rolls; and Figs. 8, 9, 10 and 11 are isometric views showing the varied character of the work which may be done by the machine.

A represents the frame of the machine which may be supported as by legs 2 on a table or other convenient means, and is provided with ways in which are mounted to slide blocks 4 forming bearings for the shaft 5 of lower roll B, and forced upwardly by springs 6, which react against the frame of the machine. Adjustable stops 8 acting against lugs formed on blocks 4 serve to limit this upward movement. Upper roll C is journaled in blocks 10 adjustable in ways in the frame A and held rigidly against yielding by wedge-shaped blocks 12 which are operated in unison by hand wheel 13. Both rolls are driven so that their adjacent surfaces move in the same direction and preferably at the same rate from an actuating shaft 14 having a pulley 16 which may be belted to any suitable source of power.

Mounted on the shaft 5 of lower feed roll B and preferably against the face of gear disk 15 for said shaft is a cam 18, herein shown as a block pivotally mounted on said shaft 5 and adjustably secured in the desired angular position on said gear disk 15 by a pin 20, mounted in said disk and engaging a slot 21 in said cam block. This cam actuates a shaft 28 through the medium of an arm 26 adjustably secured to said shaft and pivotally connected at its other end with connecting rod 24, which is pivotally mounted on shaft 5, having a slot 23 through which said shaft passes, and a roller 25 moving in contact with cam 18. Shaft 28 is mounted to rock in suitable bearings and has adjustably secured thereto a lever 30, of substantially the shape shown, which is connected by a link 31 to feed slide 32. A spring 34 may be provided for returning feed slide 32 to its initial position after its actuation by rock-shaft 28. This feed slide 32 is substantially flush with the surface of bed plate D and is provided with guides 33 on which it slides in ways formed in said bed plate. It also carries on its front end a feed plate 35 adjustably held by screw 36. This feed plate is considerably wider than slide 32, and rests at its edges which project

beyond said slide 32 upon the surface of bed plate D on which it is reciprocated. Means are provided for rendering the above described feeding device inactive, comprising a cam 38 adjustably mounted on a shaft 39 and actuated by a handle 40, and co-acting with lever 30 to rock shaft 28 and force the feed slide in to its limit of movement, in which position roller 25 is held out of contact with all parts of cam 18 as said cam is rotated. A spring 41 is also provided acting on shaft 39 and tending to turn it to the position in which the feeding movement of slide 32 is permitted to take place.

In lugs extending from the sides of the bed plate D are removably mounted rods 44 to support the adjustable sliding brackets 46, which are clamped in position by screws 45, and are provided with guides 48 on which the front pieces 50 of magazine F are adjustably mounted. These front pieces 50 preferably comprise each a block a mounted to slide on guide 48, and cast on the lower edge of a side plate b to which the side plate 52 for the magazine is removably secured by screw 49, a front plate c forming the partially inclosed front of the magazine, and a screw threaded lug d being formed on the base of front plate c. These lugs d are engaged respectively with right and left screw threads formed on the adjusting rod 54 which is mounted in brackets 46 so as to be held against longitudinal movement, and is provided with a head 55 for convenience in turning. On block a are also mounted guides 56, said guides being held so as to be adjustable independently of the magazine front pieces 50, as by means of set screws 57 and extending rearwardly beyond the sides of the magazine to guide the banks as they are fed from the magazine to the rollers and to prevent the blanks from being displaced or spreading as they are gripped between the mold and pressure roller.

At the rear of the magazine, a yoke 58 is provided, extending upwardly from the base plate of the machine, to which it is removably secured. This yoke supports a gate 60 which in effect serves to close the rear of the magazine, see Fig. 5, and has its front face curved to correspond approximately to the shape of the lifts in the magazine, and its rear face flat to contact with a supporting or bracing plate 62, extending across the base of the yoke 58. Gate 60 is supported from yoke 58 through the medium of a cross bar 64 adjustably supported from the top of said yoke, as by a screw 65 and carrying two rods 66 secured thereto and extending into hollow arms 67 extending upward from said block 60. Preferably a spring 68 will be provided between the end of each rod 66 and its hollow arm 67, to force the two apart and a short pin 69 projecting from rod 66 into a slot in its hollow arm 67 serves

to limit the amount of this movement. Preferably rods 66 are extended as shown to enter passages formed in the top of yoke 58, and serve to guide the gate 60 more accurately as it moves up and down, and other guide rods 70 may be provided, which are secured to cross bar 64 and extend through passages in lugs 72 formed on the yoke.

Upper roller C, which is herein shown as the die roller, has a smooth surface to which the die 74 is removably secured by any approved means. The shape of this die varies corresponding with the character of the work to be done by the machine, whether wedge lifts are to be split, or gouge lifts or horse shoe rands. The means of securing the die to its roller herein shown consists of a block 75 to which the die is permanently attached, and which fits flush in a recess formed in the surface of the roll, being secured therein, as shown, by screws, while the die itself extends a suitable distance around the periphery of the roll.

Lower or presser roll B has a roughened surface for more surely gripping the blanks as they are presented to knife E. Preferably said roughened surface consists of a plurality of corrugated or notched rings e between which there are smooth rings f of reduced diameter. On shaft 5 at each end of roll B there are mounted loosely stripper hangers 76, which hang downward by their own weight and are connected at their lower ends by a cross rod 78. On said rod and between the hangers 76 there are mounted a plurality of stripper plates 80 which are spaced apart by any suitable means, as washers 82, of substantially the same thickness as corrugated rings e. These plates 80 are curved at their upper ends to correspond substantially to the curvature of smooth rings f, and when the stripper is assembled extend between said corrugated rings e into contact with smooth rings f.

In the operation of this machine, a considerable number of the blanks to be split, having been died out to the proper shape and placed in magazine F resting upon bed plate D, are automatically fed forward one at a time to die roll C and presser roll B by which they are gripped and presented to the cutting edge of knife E, which splits or skives to a shape determined by the form of the die.

By turning screw 54 by its head 55, the side walls of the magazine may be adjusted to accommodate blanks of different width, while the front and side walls may be adjusted together relatively to the gate 60 which forms the rear wall of the magazine by loosening clamping screws 45 and sliding brackets 46 back and forth on rods 44. This adapts the magazine to accommodate blanks of different length. Feed plate 35 is actuated from cam 18 once for every

revolution of the rolls B and C to feed the bottom blank forward from the magazine F to said rolls, the distance said plate 35 moves forward or its point of nearest approach to said rolls being adjusted by screw 36, according to the length of the blanks being fed. To obtain the best results said plate 35 should feed the blanks forward until their forward ends are securely engaged between rolls B and C, when the remainder of the feeding will be accomplished by said rolls. From the fact that rolls B and C are driven so that their peripheries move at the same speed, and that cam 18 which actuates slide 32 is carried around on the gear disk for one of said rolls it will be seen that the movement of said slide is correlated with the rotation of the rolls so that the extreme feeding position of said slide corresponds to a certain position of said rolls in their rotation and this position can be varied by adjusting cam 18 through the medium of pin 20 and slot 21. By reason of this correlation between the movements of the feed slide and rolls the blanks will be fed forward so as to be gripped by a predetermined point on the surface of said rolls relatively to the die or molds and so that on the continued rotation of said rolls the die may act upon each part of said blank in the manner necessary to present said blank to the treating means in the desired position. By the adjustment of cam 18, above referred to, this point on the surface of the roll relative to the die, or the position of the roll in its rotation, at which the blank is gripped by the rolls, can be varied without changing the extreme feeding position of feed slide 32.

As feed plate 35 is moved forwardly, it engages the lowermost blank in the magazine and moves it toward the rolls, the remaining blanks being held back by gate 60 as indicated on Fig. 5. By turning the screw 36 the extreme rearward position of feed plate 35 can be adjusted so that the blanks will be moved by said feed plate into position to be gripped by the two presenting rolls B and C. Preferably the forward lower edge of gate 60 is beveled slightly as indicated, to assist said block to yield against springs 68 should a blank of unusual thickness be fed forward. Springs 68 are however of sufficient strength to hold said gate from yielding to permit more than a single blank to be fed forward at a time by reason of frictional contact of such blank with the blank that is being fed forward. As the blank is fed forward it is engaged on the sides by guides 56 which hold it against being displaced or yielding sidewise as it is gripped by the rolls. This feature is important, especially when blanks for horse shoe rands are to be skived, as the pressure of the die tends to force apart the

two legs of such a blank, but it is applicable also to the treatment of other forms of blanks.

In Figs. 8, 9, 10 and 11 there are illustrated a few of the various kinds of work which a machine designed according to the present invention is adapted to perform. Fig. 8 represents a gouged lift; Fig. 9 a horse shoe rand, and Figs. 10 and 11 different forms of wedge or beveled lifts. It will be noted that in work such as shown in Figs. 10 and 11, a single died-out blank of leather yields two similarly shaped lifts, one from the flesh side and one from the grain side. In the manufacture of the form of lift shown in Fig. 10 the blank is first died out substantially in the form of a square or rectangle and is then split diagonally to form two similar wedge shaped blanks, one from the grain side and one from the flesh side, each of which may be died out again to form the completed lift. In the manufacture of the form shown in Fig. 11 the blank is first died out to a suitable form and is then split slantingly so as to form two similar lifts, each having one edge beveled as represented in said figure.

Having described my invention, what I claim as new and desire to secure by Letters Patent of the United States is:—

1. A machine of the class described, having in combination, stock treating means, means including a presser roll and a die roll for presenting stock thereto, a feed slide arranged to feed stock to said rolls, mechanism for actuating said slide in timed relation with the movements of said rolls having provision for moving the slide toward the rolls to feed the stock and yielding means for returning the slide to its initial position, and means for rendering the feed slide inactive comprising mechanism under the control of the operator for preventing the return of the slide to its initial position.

2. A machine of the class described, having in combination, a knife, means including a presser roll and a die roll for forcing the stock against the knife, a slide arranged to feed the stock to said rolls, means for actuating said slide including a cam arranged to revolve with one of said rolls and a cam rod operatively connected with said slide and means whereby the cam may be adjusted with relation to its actuating roll to vary the timing of said slide.

3. A machine of the class described having, in combination, stock treating means and means for feeding stock thereto, said feeding means comprising a magazine for holding a plurality of blanks, a gate arranged to engage the ends of the blanks adjacent to the stock treating means, a support by which said gate is carried, means for raising and lowering said support and

with it said gate, and a spring acting to force said gate downwardly.

4. A machine of the class described having, in combination, stock treating means and means for feeding pieces of stock thereto, said feeding means comprising a magazine for holding a plurality of blanks, a gate arranged to engage the ends of the blanks adjacent the stock treating means, a support by which said gate is carried, means for raising and lowering said support and a spring located between said support and gate.

5. A machine of the class described, having in combination, a knife, a work supporting table provided with means for feeding a blank toward the knife and a magazine for supporting a plurality of superposed blanks in proper position upon the table to enable the lowermost blank to be advanced toward the knife by the feeding means comprising a pair of side members constructed and arranged to confine the blank between them and for adjustment toward and from each other to accommodate blanks of different widths, said members being also arranged for simultaneous adjustment toward and from the knife to accommodate blanks of different lengths, and means for preventing the advance of the blanks above said lowermost blank.

6. A machine of the class described, having in combination, a knife, a work supporting table having means for feeding a blank toward the knife and a magazine for supporting a plurality of superposed blanks upon the table in proper position to enable the lowermost blank to be advanced by the feeding means comprising a pair of members constructed and arranged to confine the rear portions of the blanks between them and for adjustment toward and from each other, said members being also arranged for simultaneous adjustment toward and from the knife and a gate intermediate said members and the knife having a surface formed for engagement with the ends of the blanks adjacent the rolls, said gate being arranged to allow the lowermost blank to be fed toward the knife and to prevent the advance of the remaining blanks.

7. A machine of the class described, having in combination, a knife, a presser roll and a die roll for advancing a blank against the knife, a slide for feeding a blank to said rolls, a magazine for holding a plurality of superposed blanks in position to enable the lowermost blank to be fed by the slide to said rolls comprising a pair of side members constructed and arranged to confine the superposed blanks between them and for adjustment toward and from each other, said side members being also arranged for simultaneous adjustment in the direction of

the line of feed, a rear section for engaging the ends of the blanks adjacent the rolls supported independently of said side sections and arranged to permit the lowermost 5 blank to be fed to the rolls, and bars carried respectively by said side sections arranged to prevent lateral displacement of the blanks as they are fed to said rolls, substantially as described.

10 8. In a machine of the class described, the combination of a roll having alternate corrugated and smooth rings on its circumference, said smooth rings being of less diameter than said corrugated rings, a shaft on 15 which said roll is mounted, hangers supported from said shaft and stripper plates supported from said hangers and having

their upper surfaces shaped to co-act with the above-mentioned smooth rings on the roll for stripping the work from said roll. 20

9. In a machine of the class described, the combination of a roll, a shaft, hangers sustained from said shaft at either end of said roll, a rod joining said hangers, and blades held in spaced arrangement on said rod and 25 co-acting with said roll to strip stock therefrom.

In testimony whereof I have signed my name to this specification in the presence of two subscribing witnesses.

JOSEPH H. POPE.
